COIN-CONTROLLED DISPENSING MECH-
ANISM AND CIRCUIT THEREFORJohn C. Koch, Campbell, Calif., assignor to S & S
Vending Machine Company, San Jose, Calif., a
corporation of California

Application August 29, 1950, Serial No. 182,112

19 Claims. (Cl. 194—10)

1

This invention relates to a coin-controlled circuit and to the coin-controlled switch that actuates the circuit. It may be used in connection with various automatic vending machines and has been found particularly useful in ice-vending machines.

One problem solved by this invention is that of getting actuation by different combinations of coins that total the same money value. For example, suppose that twenty-five pounds of ice sells for thirty cents. The purchaser may wish to use a quarter and a nickel, or three dimes, or six nickels, or two dimes and two nickels, or one dime and four nickels. It has been difficult to devise an apparatus that will respond in the same way to all such combinations. One reason for the difficulty is the fact that each denomination of coin is of different value and weight. In a device to be operated by different combinations of coins some simple compensation means must be provided, and the present invention offers a simple, practical solution to that problem. The same principles may be used to adjust for the differences between pennies and the other coins, but a discussion of combinations including nickels, dimes and quarters will serve to explain the invention.

Another problem solved by this invention has been the one of how to provide a machine which can be adjusted easily in a fool-proof manner to take care of price changes. Heretofore an expert skilled mechanic had to be called in to adjust the balances every time the price was changed. The present invention has solved this problem so now the balance mechanism can easily be adjusted for a change in price by a clerk or other usual store employee in no more time than it takes him to open up the box containing the mechanism.

Another problem solved by this invention can best be understood by considering an example. In ice-vending machines, each delivery of the ice takes from five to ten seconds after the proper combination of coins has been inserted. If a customer is able to insert another combination of coins before the ice has been delivered, he loses his coins, gets no ice, and is a dissatisfied customer. The present invention has solved this problem by incorporating a mechanism that will not take additional coins until the ice already paid for has been delivered and the cycle completed.

The invention may be used in conjunction with any well-known type of coin inserting mechanism and relates to the combination which will effect

2

the foregoing and other results to be pointed out herein.

Other features, advantages, and objects of the invention will appear from the following description of a particular embodiment of it. The description given in accordance with U. S. Revised Statutes, Section 4888, is illustrative of the principles, not coextensive with them, and is not intended to limit the invention except as required by the appended claims.

In the drawings:

Fig. 1 is a top plan view of a coin-operated mechanism embodying the principles of the invention.

Fig. 2 is a view in side elevation and in section taken generally along the line 2—2 in Fig. 1, but cut away so that the micro switch can be seen.

Fig. 3 is a detail view of the pivot point taken along the line 3—3 of Fig. 1.

Fig. 4 is a view in section taken along the line 4—4 in Fig. 1, showing the nickel coin chute in cross section.

Fig. 5 is a plan view in section of the nickel chute, taken along the line 5—5 in Fig. 4.

Fig. 6 is a view in perspective of the pivotally mounted balance mechanism.

Fig. 7 is a view in section taken along the line 7—7 in Fig. 1 showing the coin receptacle in the counterweight.

Fig. 8 is a wiring diagram of the circuit of this invention, and

Fig. 9 is a diagrammatic plan view of the balance and coin receptacle portion of the mechanism.

Before proceeding to a detailed explanation of the whole device, it will probably facilitate the understanding of the invention to explain first, in reference to Fig. 9, the several features of the balance mechanism where it is set up to receive coins of three denominations.

The balance mechanism includes a separate receptacle 61, 72 and 73 for each coin, each receptacle being mounted on arms X and Y projecting out from the pivot point Z. The arm X in Fig. 9 corresponds to the spacer 62 and a portion of the member 60. The arm Y corresponds to the arm 70 and a portion of the member 60. Projecting from the opposite side of the pivot point is a counterweight having also a coin receptacle 80 in or adjacent it mounted the same distance X from the pivot point Z as the receptacle 61 that is to receive the customer's coin of the smallest denomination used in the coin receptacle 80 in making any price changes. When there are no coins in the receptacles 61, 72, 73

and 80 the counterweight is calculated to be enough overbalanced by the weight of the receptacles 61, 72 and 73 just to actuate the energizing mechanism.

The balance mechanism can then be set by the store operator to actuate the energizing mechanism upon the deposit by the customer of any number of coins of the smallest denomination from one on up, by his placing in the coin receptacle 80 on the counterbalance, the number of such coins that are to equal the purchase price of the goods being dispensed. This means there are no delicate adjustments to be made. When the price goes up or down all the store operator does is open up the back and put in or remove from the counterbalance coin receptacle 80 the number of coins representing the price change.

For example, if the price is to be figured in multiples of 5 cents and the nickel coin is to be used, the receptacle 61 to receive the customer's nickel is mounted on an arm X that is the same distance from the pivot point Z as is the coin receptacle 80 on the counterweight. If the total purchase price is 5 cents, the store operator will place a five cent piece in the coin receptacle 80 on the counterweight. This weight is sufficient to hold the balance mechanism in level (inoperative) position until the customer's nickel drops into the receptacle 62. The customer's nickel overbalances the counterweight and the energizing mechanism is actuated. If the total purchase price is 10 cents, 15 cents, 20 cents, or 25 cents, the store operator will place in the receptacle 80 of the counterweight either 2 nickels, 3 nickels, 4 nickels, or 5 nickels respectively. The operation, for example, when set for a 25 cent purchase price, will entail the customer dropping five nickels into the receptacle 61. This will overbalance the five nickels held in the coin receptacle 80 on the counterweight, and the energizing mechanism will go to work purveying to the customer the goods paid for.

When the purchase price is ten cents or more, experience has shown that provision must be made for the customer who will not have in change the two or more nickels needed, but he may have a dime and some nickels. For example, if the price is a quarter, the customer may have a quarter, or two dimes and a nickel, or a dime and three nickels.

To care for this situation and still keep the mechanism so that the price can be changed by the store operator merely inserting or removing nickels from the coin receptacle 80 on the counterweight, the receptacles 72 and 73 to receive the customer's dime or quarter respectively (or other coin if in larger denominations) are mounted on the arm Y. Arm Y is of such a length that a customer's dime dropped in the dime receptacle 72 will balance the weight of two of the nickels put in the coin receptacle 80 on the counterweight, and a customer's quarter in its receptacle 73 will balance the weight of five of the nickels put in the coin receptacle 80 on the counterweight. In the case of a silver dime and a silver quarter a common arm Y can support their respective receptacles 72 and 73 because a quarter weighs two and a half times what a dime weighs.

This simple, fool-proof mechanism makes it possible for the store operator to change the price as market conditions dictate and without having to call a service man to make the change in the coin balance mechanism. All the store operator does is to put into the coin receptacle 80 on the counterweight the number of nickels that repre-

sent the purchase price. When the customer matches this with the deposit in the receptacle 61 of the requisite number of nickels or with coins of equivalent value in the other receptacles 72 or 73, the counterweight is overbalanced and the energizing mechanism is actuated to release to the customer the goods he paid for.

Following is a description of the mechanism by which the customer's money gets into the receptacles and how movement of the balance mechanism sets in operation the dispensing cycle so the goods are released to the customer.

The coin chutes A

(Figs. 1 and 2)

The coin introducing portions of the device are supported on a frame 10 that fits into a closed housing (not shown) or into a recess in the wall of a building (also not shown). The frame 10 includes a front plate 11 that may form the front wall of the housing or cover the front of the wall recess. The frame 10 also includes two side bars 12 and 13 that extend back from adjacent each end of the plate 11, and a rear frame 14 assembly that is secured to the bars 12 and 13. An outside coin-catching guard 15 may extend up diagonally from the lower part of the front plate 11. The guide 15 catches any small coins that are placed on the wrong coin chute and fall through, and its upper extension also prevents the coin slides from being drawn back too far.

The coin feed mechanism A includes three coin chutes which fit through a horizontal slot 16 in the plate 11. Each chute includes a slide 20 that has a round coin pocket 21 and reciprocates in a sleeve-shaped guide member 22. This guide member 22 is cast with up-standing flanges 23 through which bolts 24 may be screwed into the rear face of the plate 11 to secure the coin feed mechanism A to the frame 10.

To prevent a customer from inserting a dime into either the nickel or the quarter pocket 21, or from inserting a nickel into the quarter pocket, an opening 25 is provided leaving a ledge to support the proper coin, but providing an opening 45 through which the smaller coins will fall. A proper coin in proper position for insertion will rest in its pocket 21 flat on the bottom plate 26 of the guide 22 ready for the slide 20 to move it inwardly.

When the slide 20 is moved its full stroke it comes against a stop member 27, at which location good coins will drop through an opening 28 in the plate 26. Over each slide is a horseshoe magnet 29 to attract and hold iron slugs and prevent them from dropping through the openings 28. Upon retraction of the slide 20 a slug will be drawn back to its starting position where the customer can replace it with a good coin. Perforated coins are prevented from getting as far as the opening 28 by a dog 32 that will drop down into the perforation in the coin. For details on these and other fraud-preventing devices connected with the coin chute, reference may be had to Patent No. 2,135,710 as they form no part of the present invention.

The nickel coin chute

(Figs. 4 and 5)

The nickel coin chute is somewhat different from the others, because as will appear later in the description, the receptacle 61 into which the nickel must fall is located further back from the plate 11 than the receptacles 72 and 73 into which the dimes and quarters fall. Since the

stroke of the coin slide 20 for the nickels is the same as for the other coin slides, the difference is made up by using two nickels to fill in the space between the nickel drop out opening 46 and the coin opening 21. When in operation these two nickels are already in the machine so the customer's nickel is immediately effective to drop a nickel into the nickel receptacle 61.

Instead of falling directly from the coin receptacle opening 21 through the drop-out opening 28 into its coin receptacle as do the dimes and the quarters, each nickel first drops down onto a plate 40 secured directly beneath the opening 28 and the coin guide 22. The first nickel remains there as the slide 20 is retracted and a leaf spring pusher foot 41, secured to the lower edge of the front end 42 of the nickel slide 20 passes back over the nickel and drops down behind it. On the next stroke of the nickel slide 20 the turned-up end 43 of the spring foot 41 engages the first nickel and pushes it partway along over the plate 40, while the second nickel drops down onto the plate 40. Upon retraction of the slide 20 the foot 41 gets behind this second nickel and if the slide 20 is moved inwardly the second nickel will push the first nickel along the plate 40 until it comes under a spring 45 which is at the edge of the nickel drop-out opening 46. The nickel slot is now loaded and ready to function.

Insertion of a third nickel will allow the slide 20 to make a full stroke which will allow the foot 41 to push the second nickel under the spring 45 and will cause the first nickel to be pushed off the end of the plate 40, so it will drop down through the opening 46. Unless a third nickel is inserted in the slide opening 21, the nickel under the spring 45 cannot be released by pushing in the slide 20 because the pawl 32 will fall into the opening 21 and stop the stroke of the slide 20 before the foot 41 can reach the second nickel to move it under the spring 45 and thereby release the first nickel.

The spring 45 not only retains the nickel at the edge of the opening 46, but it also serves to support the nickel in a level position until it is almost completely over the edge of the opening 46. The spring 47 is provided in case the spring 45 should tend to tilt the nickel upwardly as it passes over the rim.

The balance mechanism

(Figs. 6, 7, 1, 2, and 3)

The general principles of this balance mechanism have already been explained. The device may take many forms depending on the designer's choice. For purposes of illustration the mechanism is shown here as including a pivoted actuator C with coin receptacles B and E. Placement of the proper weight of coins in these receptacles causes the actuator C to swing around its fulcrum D and to actuate the switch F.

The fulcrum D for the actuator C comprises a pair of knife-edge trunnions 50 secured to each side of the actuator body. The trunnions 50 are supported on bearings 51 that may be cut in the frame bars 12 and 13. (See Fig. 3). Preferably the bearing openings 52 are so shaped that the actuator C cannot swing back (counterclockwise in Fig. 2) further than its horizontal position. A stop member 53 is also provided on the rear assembly 14, comprising a bracket 54 and a threaded member 55. (See Fig. 2.)

The actuator C has three coin receptacles. The nickel coin receptacle 61 is secured close to the

actuator body 60. (Figs. 4 and 5). A spacer plate or shim 62 may be provided to space the receptacle 61 the correct distance from the fulcrum D. The nickel receptacle 61 includes a floor plate 63, a vertical rear wall 64, and two vertical side walls 65 and 66. The slope of the floor plate 63 tends to retain the coins that drop into it. The front wall of the pan 61 is open so that the coins will slide out the front end when the actuator body 60 is tilted to dump the coins and start the dispensing cycle. A plate 67 is secured to the bottom of the slide 40 closely adjacent the front of the receptacle 61 (when the actuator body 60 is in horizontal position) to prevent nickels from accidentally falling out of the receptacle.

A threaded rod 70 is secured to the front of the actuator body 60. (Figs. 1, 2, and 6.) At the outboard end of the rod 70 there is a bracket 71 to which the dime receptacle 72 and quarter receptacle 73 are secured. Since dimes and quarters have about the same weight per value their pans 72 and 73 are supported about the same distance from the fulcrum D. The receptacles 72 and 73 are similar in construction to the nickel receptacle 61, except for size and depth, and need no further explanation. A plate 74 depending from the guide plate 22 adjacent the drop-out opening 28 prevents dimes and quarters from falling out the front end of the pans 72 and 73.

An adjustable counterweight 75 is threaded on the rod 70 before installation, and is held in its proper position by a lock nut 76. This makes it possible to adjust the balance of the actuator to take care of variations in manufacture.

A solenoid core 77 depends from the rod 70 and is mounted to enter the solenoid G through an opening 78 when deposit of the requisite coins in the receptacles causes the actuator C to tip. When the solenoid G is energized it pulls the actuator C into its coin-dumping position and holds it there until the cake of ice has passed into the delivery chute.

Adjustment of the actuator counterweight for changes in price

(Figs. 1, 2, 5, 6, and 7)

It has been explained earlier, the ease with which a store manager can adjust this mechanism to care for a change in price, namely, by adding or removing coins from the counterweight. To permit this, a receptacle E is provided in the actuator body 60 on the opposite side of the fulcrum D from the receptacles B. The receptacle E is a generally cylindrical chamber 80 open on its upper and side edges and covered on the upper edge by a removable plate 81. A coil coin supporting spring 82, preferably loosely coiled, is inserted in the chamber 80 before the plate 81 is installed.

Whatever nickels 83 are in the chamber 80 are retained upright by the spring 82. These nickels are the same effective distance X from the fulcrum D as the nickel receptacle 61. Each nickel added in the chamber 80 adds five cents to the price, because it means that the customer must insert five more cents of value in the coin receptacles before the actuator C will be overbalanced. Similarly each nickel removed from the chamber 80 reduces the price to the customer five cents. Once access is had to the chamber 80, it takes only a second or two for the store clerk to change the price.

Actuation of the switch and circuit: Dumping of the coins

(Figs. 2, 6, and 8)

When the proper number of coins have been inserted in the coin feed A by the customer, and they have fallen into the coin receptacles, they will tilt the actuator C which will carry the bracket 85 into engagement with the lever 86 of a switch F, mounted on the frame 10. (See Figs. 2 and 6.)

Actuation of the switch F initiates the dispensing cycle. Among other things, as explained in the section entitled "The circuit," it energizes the solenoid G, the core 77 of which is pulled into the magnet until it strikes the bottom plate. This carries the actuator body C and the coin receptacles into position where the coins fall out of the receptacles. The jar on the coin receptacles as the solenoid draws the core against the bottom plate will in most cases remove the coins. Any that remain will gradually fall out of the receptacles due to the vibration transmitted to the receptacles from the alternating current in the solenoid. The actuator is retained in this position until the circuit is de-energized, following which the counterweight C lifts the coin receptacles back up under the coin drop out openings 28 and 46.

Coin lock-out during the dispensing cycle

(Figs. 1, 2, 4, and 8)

A mechanism is provided to lock-out further coins and prevent their insertion by a customer until a cycle in progress has been completed. This mechanism includes the solenoid H and a plurality of lock out bars 90, one for each coin feed chute. Each bar 90 has a small stud 91 at its inner end for pivotal mounting in a pocket 92 between the arms of the horseshoe magnet 30. Near its forward end the bar 90 has a shoulder 93 that limits its downward movement by engaging the upper surface of the coin guide frame 22. The vertical face 94 of the bar projects into the path of the coin slide 20. If the latter is pushed in it will hit the shoulder 94 before it can move its full stroke. A coin cannot be inserted far enough to fall through the openings 28 or 46 unless the lock out bar 90 is lifted out of the way.

Normally the bars 90 are held up by solenoid H where they will not lock out the coin slides 20. A horizontal rod 95 passes beneath the fore part 96 of each bar 90 and is secured to a core 97 of the solenoid H. When the solenoid H is energized, the core 97 and the rod 95 are lifted, which holds the lock out bars 90 out of the way of the slide 20. Solenoid H is energized at all times, except during a delivery cycle or when the lever 151 drops. When it is de-energized, a leaf spring 98 mounted over the center coin chute 20 assists the force of gravity in overcoming any residual magnetism or friction in dropping the lock out bars 90.

The circuit

(Fig. 8)

A source of alternating current is used, preferably 110 volts at 60 cycles, although other voltages and frequencies may be used. Preferably one line 100 is "hot" and the other line 101 is grounded so as to be neutral. A main control switch 102 is available for the user to shut down the device at night or for repairs.

The 24 volt circuit originates in a 110-volt to

24-volt transformer 120 placed across the input lines 100 and 101 and having a hot output lead 121 and a grounded output lead 122.

A resistor 112 may be placed in parallel with the motor 110 to warm the relay box inside the ice vending machine to keep it from freezing. It is not necessary otherwise.

Two separate circuits are used in connection with a two-pole single throw relay 103. One is the 110 volt circuit that energizes the motor M on the dispensing belt mechanism. The other is the 24 volt circuit that controls the solenoids, relays, etc.

The relay 103 is energized when the customer's coins tilt the actuator C and close the micro switch contact at 141 to initiate the dispensing cycle.

The 110 volt motor drive circuit includes the leads 108, 109, 111, and is connected to the relay contacts 104 and 105 so that the upper contact bar 107 on the relay 103 closes the circuit. The motor 110 moves a conveyor belt J shown diagrammatically in Fig. 8 to dispense one block of ice (or other unit-packed merchandise) on each cycle and to move a block of ice up to the ready position to take the place of the one dispensed. The motor 110 operates only when the relay 103 is energized and stops the instant a cake of ice is dispensed. The relay 103 is de-energized when the dispensed cake of ice slides off the belt into the delivery chute K at which time the cake of ice engages the arm 150 on the limit switch 123 and opens the circuit at 123a.

Unless there is more ice in the box ready to be dispensed and unless the cake of ice next to be dispensed is up at the ready position, the arm 151 on the limit switch 124 will drop down into the dotted line position (Fig. 8) and will open the contacts at 124a so that the whole control circuit will be de-energized. This means that the solenoid H will also be de-energized so the customer's money cannot be inserted far enough to drop into the receptacles to tilt the actuator C. When ice is in the machine ready to be dispensed the arm 151 will be held up so the contacts at 124a will be closed.

From the transformer 120 the 24 volt circuit runs through the lead 121 to the normally closed limit switch 124, then through the lead 125 to the normally closed limit switch 123, then through the lead 126 to a point 123a where the circuit branches. One branch runs through the lead 128 to the switch arm 140 then to the normally closed contact point 145, then to lead 146 to the relay H and through the lead 147 to ground. This latter part of the circuit keeps the solenoid H energized which holds the coin lock-out bars elevated so that a customer's coins can be received into coin receptacles on the actuator.

When the customer's coins fall into the receptacles on the actuator C and the projection 85 moves the switch lever 86, it moves the two switch arms 140 and 86a, each of which closes different circuits. The switch arm 86a completes the circuit through the contact 86b for the solenoid G which imparts a sudden movement to the actuator C to dislodge the coins from the receptacles and it holds down the actuator C until the ice block is dispensed. The switch arm 140 closes the circuit at the contact point 141 through the lead 133, 134 to the relay 103 which lifts the bar 132 to close the contacts 130 and 131 and the contacts 104 and 105. As explained earlier, this starts the motor cycle on the dispensing operation.

Going back to the point 126a, the other branch of the circuit goes through the lead 127 to the contact point 130, then through the bar 132 to the contact point 131 and through the lead 134 into the relay 103 and to the other side of the circuit through the lead 135. This is a holding circuit and assures that the relay 103 will hold the motor circuit closed until the conveyor has moved a block of ice into the delivery chute. As the block of ice passes down the delivery chute, it actuates the arm 150 on the normally closed limit switch 123 which breaks the circuit to the relay 103 and also breaks the circuit to the solenoid G. The counterweight on the actuator C then lifts the coin receptacles back into their position ready to receive the next insertion of coins. It also moves the switch arm 140 back to close the contact at 145 which energizes the solenoid H to lift the bars 90 out of the path of the money coin slides 20.

A counter 137 may be provided and will be actuated by a magnet through the branch circuit 136 and 138.

It is believed that the foregoing makes the operation clear. Briefly what takes place is as follows: When there is ice in the machine to be dispensed it supports the arm 151 to close the limit switch contact 124a. This energizes the solenoid H which supports the lock out bars 90. When the customer has inserted in the coin slides 20 the requisite coins and has moved these in so that the coins will drop into the receptacles 61, 12, 73, the actuator C will tilt downwardly thereby effecting movement of the switch arm 86 which energizes the solenoid G to pull the actuator into its full downward position and to dislodge the coins from the receptacles. The movement of the actuator C also opened the circuit to the solenoid H which allows the lock out bars 90 to drop so that no more coins can be inserted by the slides 20 until the cycle underway is completed. The switch arm 140 was moved by the switch lever to close the contact at 141 which energizes the relay 103 thereby closing the motor circuit and starting movement of the conveyor belt J to propel a cake of ice over the end of the conveyor belt. When the cake of ice falls into the delivery chute K it moves the arm 150 thereby opening the normally closed limit switch 123 which de-energizes the solenoid G and allows the actuator to swing back to normal position and it also opens the circuit to the relay 103 which breaks the circuit to the conveyor motor. If there is still a cake of ice on the conveyor belt supporting the arm 151 on the normally closed limit switch 124, the circuit to the solenoid H will be energized and it will hold up the lock out bars 90 so that coins may be inserted by a customer to effect the purchase of the next cake of ice.

I claim:

1. In an automatic, coin-tilted actuating mechanism for initiating a cycle in a vending machine, the combination of a pivoted counterbalanced actuator; a plurality of coin receptacles secured to said actuator on the side opposite said counterbalance; arms supporting said coin receptacles at predetermined distances from said pivot; a coin receptacle on said counterbalance, said receptacle being the same distance from said pivot as the oppositely arranged coin receptacle closest to said pivot; and means for depositing coins in said arm supported coin receptacles; said counterbalance being of a weight which is overcome by the deposit in any opposite coin receptacle of a coin, said coin receptacle on said

counterbalance being adapted to receive one or more nickels, the opposite coin receptacle closest to said pivot being adapted to receive nickels, and the other opposite coin receptacles being spaced from said pivot so that a dime dropped in one will equal in weight two nickels in the coin receptacle on said counterbalance and a quarter dropped in one will equal in weight five nickels in the coin receptacle on said counterbalance.

2. A coin-operated device adapted to receive different denominations of coins and to actuate a cycle of operation upon deposit of a predetermined total value, including in combination a frame member; an actuator body member supported by said frame member for swinging movement about a fulcrum point upon the application of a predetermined moment of force; a plurality of coin receptacles corresponding in number to the coins which are to be used; spacing means for holding said receptacles rigidly to said body member at a distance from said fulcrum point corresponding to the relative weight-per-value of each coin; a plurality of coin insertion means supported by said frame member for impelling each type of coin to a drop-out opening therethrough above its proper receptacle; an electric circuit; a switch secured to said frame member for controlling said electric circuit; switch-throwing means secured to said actuator body member to throw said switch when said body member is tilted by the predetermined value of coins; a solenoid energized by said actuator throwing said switch; and a solenoid core secured to said actuator and adapted to be pulled into said solenoid when said solenoid is energized to cause said actuator to swing far enough to dump the coins from the receptacle and to be held there until said solenoid is de-energized.

3. A coin-operated device adapted to receive different denominations of coins and to actuate a cycle of operation upon deposit of a predetermined total value, including in combination a frame member; an actuator body member supported by said frame member for swinging movement about a fulcrum point upon the application of a predetermined moment of force; a plurality of coin receptacles corresponding in number to the coins which are to be used; spacing means for holding said receptacles rigidly to said body member at a distance from said fulcrum point corresponding to the relative weight per value of each coin; a plurality of coin insertion means supported by said frame member for impelling each type of coin to a drop-out opening therethrough above its proper receptacle; an electric circuit; a switch secured to said frame member for controlling said electric circuit; switch-throwing means secured to said actuator body member to throw said switch when said body member is tilted by the predetermined value of coins; a solenoid energized by said actuator throwing said switch; a solenoid core secured to said actuator and adapted to be pulled into said solenoid when the solenoid is energized to cause said actuator to swing far enough to dump the coins from the receptacles and to be held there until said solenoid is de-energized; and a normally closed relay in said circuit that is opened momentarily upon delivery of merchandise so as to de-energize said solenoid and permit the return of said actuator body member to its normal position.

4. A coin-operated device adapted to receive different denominations of coins and to actuate

a cycle of operation upon deposit of a predetermined total value, including in combination a frame member; an actuator body member supported by said frame member for swinging movement about a fulcrum point upon the application of a predetermined moment of force; a plurality of coin receptacles corresponding in number to the coins which are to be used; spacing means for holding said receptacles rigidly to said body member at a distance from said fulcrum point corresponding to the relative weight-per-value of each coin; a plurality of coin insertion means supported by said frame member for impelling each type of coin to a drop-out opening therethrough above its proper receptacle; an electric circuit; a switch secured to said frame member for controlling said electric circuit; switch-throwing means secured to said actuator body member to throw said switch when said body member is tilted by the predetermined value of coins; and a lock-out mechanism acting to prevent the insertion of coins during a cycle of operation initiated by a previously inserted coin, said lock-out mechanism including in combination a plurality of lock-out bars mounted for movement up and down and positioned when in their lower position to intercept the path of said coin insertion means to prevent their entry into the device to their coin depositing position; solenoid-operated means to raise said bars out of the way of said coin insertion means, said solenoid being de-energized when said switch is thrown and thereby dropping said bar; and switch means to effect a re-energization of said solenoid upon the completion of a cycle.

5. A coin-operated device adapted to receive different denominations of coins and to actuate a cycle of operation upon deposit of a predetermined total value, including in combination a frame member; an actuator body member supported by said frame member for swinging movement about a fulcrum point upon the application of a predetermined moment of force; a plurality of coin receptacles corresponding in number to the coins which are to be used; spacing means for holding said receptacles rigidly to said body member at a distance from said fulcrum point corresponding to the relative weight-per-value of each coin; a plurality of coin insertion means supported by said frame member for impelling each type of coin to a drop-out opening therethrough above its proper receptacle; an electric circuit; a switch secured to said frame member for controlling said electric circuit; switch-throwing means secured to said actuator body member to throw said switch when said body member is tilted by the predetermined value of coins; and a lock-out mechanism serving to prevent the insertion of coins during a cycle of operation initiated by a previously inserted coin, said lock-out mechanism including in combination a plurality of lock-out bars corresponding in number to said insertion means, each bar being mounted pivotally adjacent one end for movement of the other end up and down, a portion near said latter end when in its lower position intercepting the path of its associated coin insertion means and preventing its entry into the device and its movement to its coin depositing position; a yoke means passing beneath said latter end portion of all said bars; a solenoid-operated means to raise said yoke means and lift all of said bars above their interception position, said solenoid being energized by said circuit, and being de-energized when said actuator throws

said switch and remaining de-energized until said actuator returns and said switch returns to its original position upon the completion of a cycle.

6. A coin-operated device adapted to receive different denominations of coins and to actuate a cycle of operation upon deposit of a predetermined total value, including in combination a frame member; a counterweighted actuator body member supported by said frame member for swinging movement about a fulcrum point upon the application of a predetermined moment of force; a plurality of coin receptacles corresponding in number to the selection of coins which may be used; spacing means for holding said receptacles rigidly to said body member at a distance from said fulcrum point corresponding to the relative weight-per-value of each coin; a plurality of coin insertion means supported by said frame member for impelling each type of coin to a drop-out opening therethrough above its proper receptacle; the coin insertion means for the coin whose receptacle is nearer the fulcrum point than the other coin receptacles including in combination a guide sleeve extending into a drop-out opening inside said device; a slide way positioned below said guide sleeve drop-out opening and extending beyond it to provide its own drop-out opening; a coin insertion member for said coin being movable in said guide sleeve and having a pocket to receive a coin so that said coin may be propelled along said guide to said sleeve drop-out opening first mentioned, when said insertion member is moved in said sleeve; a pusher member secured adjacent and extending beyond the inner end of said insertion member, being adapted to engage a coin that has fallen through said sleeve drop-out opening and to propel it toward said slide way drop-out opening; and a leaf spring secured over said slide way adjacent said slide way drop-out opening to prevent premature movement of coins thereto.

7. A coin-operated device adapted to receive different denominations of coins and to actuate a cycle of operation upon deposit of a predetermined total value, including in combination a frame member; a counterweighted actuator body member supported by said frame member for swinging movement about a fulcrum point upon the application of a predetermined moment of force; a plurality of coin receptacles corresponding in number to the selection of coins which may be used, said receptacles comprising a wall open on the side more distant from the fulcrum and a floor inclined down in the direction toward said fulcrum; spacing means for holding said receptacles rigidly to said body member at a distance from said fulcrum point corresponding to the relative weight-per-value of each coin; and a plurality of coin insertion means supported by said frame member for impelling each type of coin to a drop-out opening therethrough above its proper receptacle.

8. The device of claim 6 in which an additional leaf spring is secured above said slide way drop-out opening to limit any upward bounce impelled by the first leaf spring and cause said coin to fall flat into said receptacle.

9. The device of claim 7 in which there is a plate depending from the frame adjacent the open front end of said receptacles when said actuator is in its horizontal position, to prevent coins from spilling therefrom.

10. A coin chute for a coin operated device including in combination, a guide sleeve extending in to a drop-out opening inside said device;

a slide way positioned below said guide sleeve drop-out opening and extending beyond it to its own drop-out opening; a coin insertion member movable in said guide sleeve and having a pocket to receive a coin so that said coin may be propelled along said guide to said sleeve drop-out opening when said insertion member is moved inwardly in said sleeve; a pusher member secured adjacent and extending beyond the inner end of said insertion member, being adapted to engage a coin that has fallen through said sleeve drop-out opening and to propel it toward said slide way drop-out opening; and a leaf spring secured over said slide way adjacent said slide way drop-out opening to prevent premature movement of coins thereto.

11. The chute of claim 10 in which there is an additional leaf spring secured directly over said slide way drop-out opening to prevent coins from being urged upward or out of a flat position.

12. A lock-out mechanism for a coin-operated device having a plurality of coin-impelling slide means, said mechanism serving to prevent the insertion of coins during a cycle of operation initiated by previously inserted coins, and including in combination a plurality of lock-out bars corresponding in number to said slide means, each bar being mounted pivotally adjacent one end for movement up and down of the other end, a portion near said latter end when in its lower position intercepting the path of its associated coin slide means and preventing its entry into the device and its movement to its coin-depositing position; a yoke means passing beneath said latter end portion of all said bars; a solenoid operated means to raise said yoke means and lift all of said bars above their interception position; means to deenergize said solenoid and drop said yoke means and bars on the initiation of a cycle; and means to reenergize said solenoid upon the completion of a cycle.

13. A coin-operated device adapted to receive different denominations of coins and to actuate a cycle of operations upon deposit of a predetermined total value, including in combination a frame member; a counterweighted actuator body member supported by said frame member for swinging movement about a fulcrum point upon the application of a predetermined moment of force, said actuator body member having a chamber adapted to receive coins of the denomination having the least weight-per-value of the coins accepted by the device so that the value of coins to be deposited by the customer may be changed by inserting coins in or removing coins from said chamber; a plurality of coin receptacles corresponding in number to the selection of coins which may be used; spacing means for holding said receptacles rigidly to said body member at a distance from said fulcrum point corresponding to the relative weight-per-value of each coin; and a plurality of coin insertion means supported by said frame member for impelling each type of coin to a drop-out opening therethrough above its proper receptacle.

14. A coin-operated actuation device adapted to receive different denominations of coins and to move to its actuating position upon deposit of a predetermined total value, including in combination an actuator body member supported for swinging movement about a fulcrum point upon the application of a predetermined moment of force, said body member being provided with a recess parallel to the pivot line of the member and adapted to receive coins of the denomination of the least weight-per-value received by the

device; a plurality of coin receptacles corresponding in number to the different types of coins which are to be received; and spacing means for holding each of said receptacles rigidly to said body member at a distance from said fulcrum point corresponding to the relative weight-per-value of each coin, whereby it takes more coins of lower value to create the predetermined moment than it takes coins of higher value; the recess in said body member being on the opposite side of the fulcrum from said receptacles and adapted to hold its coins at the same effective distance from the fulcrum as the receptacle closest to the fulcrum.

15. The device of claim 14 in which a loose coil spring is disposed in said recess to maintain said coins in position.

16. A coin chute for a coin-operated device including in combination, a guide sleeve extending into a drop-out opening inside said device; a slide way positioned below said guide sleeve drop-out opening and extending beyond it to its own drop-out opening; a coin insertion member movable in said guide sleeve and having a pocket to receive a coin so that said coin may be propelled along said guide to said sleeve drop-out opening when said insertion member is moved inwardly in said sleeve; a pusher member secured adjacent and extending beyond the inner end of said insertion member, being adapted to engage a coin that has fallen through said sleeve drop-out opening and to propel it toward said slide way drop-out opening; and restraining means along said slide way for controlling movement of coins therethrough and braking their momentum at the end of the inward stroke of said pushing means.

17. A coin-operated device adapted to actuate a cycle of operation upon deposit of a predetermined value of coins, including in combination a frame member; an actuator body member supported by said frame member for swinging movement about a fulcrum point upon the application of a predetermined moment of force; at least one coin receptacle held rigidly by said body member; coin insertion means supported by said frame member for depositing each coin in its coin receptacle; an electric circuit; a switch secured to said frame member for controlling said electric circuit; switch-throwing means secured to said actuator body member to throw said switch when said body member is tilted by the predetermined value of coins; a solenoid energized by said actuator throwing said switch; a solenoid core secured to said actuator and adapted to be pulled into said solenoid when the solenoid is energized to cause said actuator to swing far enough to dump the coins from the receptacles and to be held there until said solenoid is deenergized; and a normally closed relay in said circuit that is opened momentarily upon delivery of merchandise so as to deenergize said solenoid and permit the return of said actuator body member to its normal position.

18. A coin-operated device adapted to actuate a cycle of operation upon deposit of a predetermined value of coins and to prevent the deposit of further coins until completion of the cycle, including in combination a frame member; an actuator therein having a plurality of coin receptacles and responsive to the application of the predetermined value of coins; a plurality of coin insertion means supported by said frame member for impelling each type of coin to and depositing it in its proper receptacle; an electric circuit; a switch secured to said frame member

for controlling said electric circuit; switch-throwing means secured to said actuator to throw said switch when said actuator has received the predetermined value of coins; and a lock-out mechanism acting to prevent the insertion of coins during a cycle of operation initiated by a previously inserted coin, said lock-out mechanism including in combination a plurality of lock-out bars mounted for movement up and down and positioned when in their lower position to intercept the path of said coin insertion means to prevent their entry into the device to their coin depositing position; solenoid-operated means to raise said bars out of the way of said coin insertion means, said solenoid being de-energized when said switch is thrown and thereby dropping said bar; and switch means to effect a re-energization of said solenoid upon the completion of a cycle.

19. A coin-operated device adapted to actuate a cycle of operation upon deposit of a predetermined total value, including in combination a frame member; an actuator supported therein and responsive to the application of said predetermined total value; a plurality of coin receptacles on said actuator; a plurality of coin insertion means supported by said frame member for impelling each type of coin to its proper receptacle; the coin insertion means for at least one receptacle including in combination a guide

5 sleeve extending in to a drop-out opening inside said device; a slide way positioned below said guide sleeve drop-out opening and extending beyond it to provide its own drop-out opening; a coin insertion member for said coin being movable in said guide sleeve and having a pocket to receive a coin so that said coin may be propelled along said guide to said sleeve drop-out opening first mentioned, when said insertion member is moved in said sleeve; a pusher member secured adjacent and extending beyond the inner end of said insertion member, being adapted to engage a coin that has fallen through said sleeve drop-out opening and to propel it toward said slide way drop-out opening; and a leaf spring secured over said slide way adjacent said slide way drop-out opening to prevent premature movement of coins thereto.
